UNITED STATES PATENT OFFICE.

JAMES I. WARREN, OF OTTUMWA, IOWA.

LUBRICATOR.

No. 845,209.

Specification of Letters Patent.

Patented Feb. 26, 1907.

Application filed December 7, 1906. Serial No. 346,688.

To all whom it may concern:

Be it known that I, **JAMES I. WARREN**, a citizen of the United States, residing at Ottumwa, in the county of Wapello and State of Iowa, have invented certain new and useful Improvements in Lubricators; and I do hereby declare that the following is a full, clear, and exact description of the same, reference being had to the annexed drawings, making a part of this specification, and to the letters and figures of reference marked thereon.

The present invention has for its object to provide a grease-cup or lubricator of that class in which a piston or plunger is employed, a spring bearing thereon, and means for adjusting the tension of the spring; and the purpose thereof is to materially improve the construction of such device whereby a perfect action of the piston or plunger is obtained, the tension of the spring easily and readily adjusted and held in its adjustment by a spring-actuating means, and in other respects providing a simple and effective grease-cup or lubricator.

The invention consists in a lubricator constructed substantially as shown in the drawings and hereinafter described and claimed.

Figure 1 of the drawings is a sectional elevation of a lubricator constructed in accordance with my invention; Fig. 2, a perspective view of the regulating-nut; Fig. 3, a similar view of the spring which engages the nut.

In the accompanying drawings, A represents a suitable receptacle for containing the lubricant, and within this receptacle above the lubricant is a piston B, having a coiled spring a, encircling the stem b of said piston and bearing thereon at its lower end. The stem b of the piston B extends up through a screw-threaded extension C, depending from a flat-sided nut D and also through the nut, as shown in Fig. 1 of the drawings.

The exterior screw-threads upon the extension C engage interior screw-threads on the upper end of the receptacle A, and said extension has a mortised seat c upon the under side thereof for the upper end of the spring a to hold the spring in position, said

spring being larger at one end and smaller at the other, which makes a more uniform feed.

A flat curved spring E is employed to keep the guide-nut and its extension from working out, the lower end of the spring being doubled upon itself, as shown at d, to increase its strength at lower end, as shown in Fig. 3 of the drawings. The upper end of the spring E is curved around and terminates in a finger e to engage a notch f on the nut D, as shown in Fig. 1 of the drawings.

The double end d of the spring is seated in a groove g in the extension C, and the spring extends above the upper end of the receptacle A, where it may be readily manipulated.

The spring keeps the screw extension C from turning and may be readily released when desired for turning the nut by first releasing the finger e from the notch f and withdrawing the spring.

The construction of the spring E serves the double purpose of two springs, the bent-up portion d forming an auxiliary spring to hold the lower end thereof in frictional contact with the interior wall of the receptacle A and the upper portion or mainspring adapted to engage the nut D, thus providing a double spring to prevent the extension C from turning when once adjusted and set.

Having now fully described my invention, what I claim as new, and desire to secure by Letters Patent, is—

A lubricator comprising a suitable receptacle for the lubricant, a spring-actuated piston therein, a flat-sided nut with screw-threaded extension, having a notch and grooved seat respectively, and a locking-spring, the lower end of the spring being doubled upon itself to form an auxiliary spring adapted to engage the grooved seat in the extension and the upper end of the spring being curved and terminating in a finger to engage the notch in the nut, substantially as and for the purpose set forth.

In testimony whereof I affix my signature in presence of two witnesses.

JAMES I. WARREN.
